UNITED STATES PATENT OFFICE.

WILLIAM S. NOYES, OF CHICAGO, ILLINOIS.

DESIGN FOR A SPROCKET-WHEEL AND CHAIN GUARD.

SPECIFICATION forming part of Design No. 26,951, dated April 20, 1897.

Application filed March 9, 1897. Serial No. 626,684. Term of patent 3½ years.

To all whom it may concern:

Be it known that I, WILLIAM S. NOYES, a citizen of the United States, and a resident of Chicago, in the county of Cook and State of Illinois, have invented and produced a new and original Design for Sprocket-Wheel and Chain Guards or Shields for Bicycles, of which the following is a specification.

In the accompanying drawings, Figure 1 is a perspective of a guard embodying my design. Fig. 2 is a transverse section.

A guard or shield of my design consists of a marginal frame A, the edges of which are continuous or unbroken and which embodies a flange A', which projects laterally therefrom when applied to a bicycle to cover the chain. At its forward end said guard is provided with a ring or circular portion A², the rear sides of which are connected with the marginal frame A by braces or webs a.

In the rear of the circular web A² of a guard or shield of my design the opposite sides of the marginal frame A are connected by a web of open-work, consisting of letters of the alphabet combined to form a word or words, together with an ornamental scroll, as shown.

I claim—

The design for a sprocket-wheel and driving-chain guard or shield for bicycles, substantially as herein shown and described.

In testimony that I claim the foregoing as my invention I hereunto set my hand, this 3d day of March, 1897, in the presence of two witnesses.

WILLIAM S. NOYES.
